UNITED STATES PATENT OFFICE.

ROBERT W. CRAWFORD, OF FORT DODGE, IOWA.

METAL-AND-WOOD RAILWAY-TIE.

SPECIFICATION forming part of Letters Patent No. 766,328, dated August 2, 1904.

Application filed March 14, 1904. Serial No. 198,180. (No model.)

To all whom it may concern:

Be it known that I, ROBERT W. CRAWFORD, a citizen of the United States, residing at Fort Dodge, in the county of Webster and State of Iowa, have invented a new and useful Metal-and-Wood Railway-Tie, of which the following is a specification.

My object is to retain all the advantages of the resiliency of wood as a base for track-rails in a railroad and to secure the strength and utility of metal in the main portion of a cross-tie.

A further object is to produce a broad tie of comparatively light weight and great strength with means for detachably fastening wooden base-pieces securely on its end portion as required for supporting track-rails in elevated positions relative to the ground and preventing the wood from decay and in exposed positions, so the wood can be readily adjusted relative to metal boxes, in which it is inclosed, whenever necessary on account of shrinking or wearing and also readily replaced when worn out.

My invention consists in the construction, arrangement, and combination of elements and subcombinations, as hereinafter set forth, pointed out in my claims, and illustrated in the accompanying drawings, in which—

Figure 1 is a perspective view of a metal box specially adapted for retaining a wooden base for a rail at the end portion of a cross-tie. Fig. 2 is a corresponding view of the same box provided with a flange at one end to restrict the longitudinal movement of the wood relative to the box and a cross-tie. Fig. 3 is a perspective view of my metal tie having wooden base-pieces detachably fastened on its top and end portions as required for practical use. Fig. 4 is a transverse sectional view of two of my cross-ties in position as required to support a track-rail.

The numeral 10 designates a metal box that is open at its ends and top and narrower at one end than the other end and also narrower at the top than at its bottom as required to produce a vertical and also a longitudinal dovetail bearing for a wooden block

of corresponding shape and size, as shown in Fig. 3. 50

Fig. 2 shows an integral vertical flange 12 at the bottom of the narrowest end of the box that will prevent a wooden block from further inward movement in the box and aid in retaining the wood in place in the box as required to serve as a stationary fixed base for a rail. 55

The metal cross-tie 13 consists of a straight length that is corrugated, as shown, or in any suitable way as required to reduce weight and at the same time increase its bearing-surface. 60

It is obvious the metal boxes and metal tie may be made of wrought metal or cast in molds and vary in size and weight, as desired.

The boxes 10 are riveted fast on the top and end portions of the corrugated metal tie 13 and their narrowest ends near the ends of the tie and the wooden blocks 14 fitted in the boxes in dovetail position to slide outward relative to the ends of the boxes and the tie 70 and to wedge fast in the boxes, and to prevent movement of the blocks in the boxes spikes are driven through perforations in the boxes and into the wood.

The wood is properly seasoned and its pores 75 may be filled with preservative matter.

A complete cross-tie is thus produced principally of metal and the metal adapted in form for fixing comparatively small pieces of wood to its end portions to serve as cushions and supports upon which to advantageously fix rails in a common way by means of spikes, as shown in Fig. 4.

Having thus set forth the purpose of my invention and its construction and manner of use, its practical utility will be obvious to railroad men and persons familiar with the art to which it pertains, and what I claim as new, and desire to secure by Letters Patent, is—

1. In a railway-tie, a metal box open at its ends and top, narrower at one end than the other and also narrower at its top than at its bottom to produce a longitudinal and also a vertical dovetail bearing for a wooden block, for the purposes stated. 90

2. In a railway-tie, a metal box open at its

ends and top, narrower at one end than the other and also narrower at its top than at its bottom to produce a longitudinal and also a vertical dovetail bearing for a wooden block 5 and a wooden block fitted in the box, for the purposes stated.

3. A metal box for a railway-tie larger at one end than its other end and open at its top and ends to admit a wooden block in the manner set forth for the purposes stated.

4. A metal box for a railway cross-tie, wider at one end than its other end and one end partly closed and the other end and also its

top open for the reception of a wooden block and base for the support of a track-rail, in the 15 manner set forth for the purposes stated.

5. A railway-tie comprising a metal cross-piece corrugated lengthwise, metal boxes fixed on top of its end portions and wooden blocks fixed in the metal boxes, arranged and combined to operate in the manner set forth for the purposes stated.

ROBERT W. CRAWFORD.
